ATTORNEY.

UNITED STATES PATENT OFFICE

ALVIN D. NIEMEYER, OF ST. LOUIS, MISSOURI

DESIGN FOR AN ICE-CREAM CONE

Application filed December 8, 1930. Serial No. 37,906. Term of patent 14 years.

To all whom it may concern:

Be it known that I, ALVIN D. NIEMEYER, a citizen of the United States, residing in the city of St. Louis, in the State of Missouri, have invented a new, original, and ornamental Design for an Ice-Cream Cone, of which the following is a specification, reference being had to the accompanying drawing, forming part thereof.

I claim:

The ornamental design for an ice cream cone, as shown.

ALVIN D. NIEMEYER.
